UNITED STATES PATENT OFFICE.

MICHAEL LOUIS HENRY AND MICHAEL HENRY, OF TERRE HAUTE, INDIANA.

GREASE-CUP.

1,137,858.

Specification of Letters Patent.

Patented May 4, 1915.

Application filed June 5, 1914. Serial No. 843,243.

To all whom it may concern:

Be it known that we, MICHAEL LOUIS HENRY and MICHAEL HENRY, citizens of the United States, residing at Terre Haute, in the county of Vigo and State of Indiana, have invented new and useful Improvements in Grease-Cups, of which the following is a specification.

This invention relates to grease cups and is in the nature of an improvement upon and simplification of the patent granted to Michael Henry, #1,012,546, dated December 19, 1911.

The object of the present invention is to provide simple and reliable means which will facilitate the application of the cap to the cup and at the same time facilitate the refilling of the cup with grease, also insuring the retention of the cap upon the cup and the proper operation of the expressing plunger.

With the above and other objects in view, the invention consists in the novel construction, combination and arrangement of parts, as will be hereinafter more fully described, illustrated and claimed.

In the accompanying drawings:—Figure 1 is a perspective view of the complete cup of this invention ready for application to any bearing. Fig. 2 is a diametrical section through the complete cup in line with the vertical portions of the locking grooves. Fig. 3 is a similar view taken in line with oppositely located notches. Fig. 4 is a side elevation of the cup omitting the cap. Fig. 5 is an inside fragmentary view of the cap, showing one of the locking lugs. Fig. 6 is a plan view of the cup omitting the cap. Fig. 7 is a detail perspective view of the cap spring.

Referring to the drawings 1 designates the cup proper which is in the form of a hollow cylindrical body exteriorly threaded at 2 to enable it to be screwed into place, and having a jamb nut 3 formed with notches 4 to facilitate tightening the same.

Both ends of the cup are left open to receive and discharge the grease and over the upper end of the cup is fitted a flanged cap 6 which is adapted to be turned manually on the cup and also moved upwardly or downwardly for the purpose of attaching and detaching the cap as will presently appear. Adjacent to its upper end the cup 1 is provided at diametrically opposite places with bayonet grooves each comprising a ver-

tical or upright portion 7 and a portion 8 extending perpendicularly to the portion 7 and partially around the cup adjacent to the upper end thereof, the portions 7 and 8 of each groove joining each other in the form of an elbow which is slightly curved as shown at 9 to facilitate the application of the cap to the cup and the removal of the same therefrom. The upright portions 7 of the grooves intersect the top edge of the cup so as to receive the locking lugs of the cap hereinafter referred to. The portion 8 of said grooves is also provided with the extension notches 10 along the upper side thereof, the purpose of which will appear.

Mounted for movement longitudinally within the cup 1 is a plunger 11 for expressing the grease from the cup and extending upwardly from said plunger is a plunger stem 12 which is slidable through an opening 13 in the center of the cap 6, a helical spring 14 encircling the stem 12 and bearing at one end against the plunger 11 while the opposite end thereof is seated against a longitudinally bowed cap retaining spring 15 the central portion of which is formed with a hole 16 to receive the plunger stem and the opposite ends of which bear against the top edge of the cup 1 at diametrically opposite points. Centrally the spring 16 bears against the inside wall of the top of the cap 6 so that said spring exerts an outward pressure against the cap for retaining the same in place on the cup and preventing the cap from jarring loose.

Internally the cap 6 is provided with diametrically opposite locking lugs 17 which are movable in the grooves in the cup, said lugs 17 being provided on their upper sides with rounded bosses 18 of the same shape as the notches 10 above referred to, the bowed spring 15 serving to hold the bosses 18 in engagement with the notches 10, thereby preventing the cap from turning either axially or moving longitudinally with respect to the cup so as to accidentally jar loose. 19 designates a pin inserted through an opening 20 in the outer extremity of the stem 12 so that when the cap 6 is removed, the plunger 11 and all parts interposed between the plunger and cap and including the helical spring 14 and the bowed spring 15 will be removed with the cap thus leaving the cup empty and in readiness to be refilled with grease.

The cap is removed by giving a partial

turn or axial movement thereto and then 5 sliding the cap in a longitudinal direction off the cup, the lugs 17 passing outward through the portions 7 of the locking grooves. After the cup is refilled with grease, the operation just referred to is reversed, the cap being slid longitudinally over the top of the cup causing the lugs 17 to move along the portions 7 and 8 of the locking grooves until the bosses 18 engage the notches 10. Thereafter the spring 15 serves to hold the cap locked on the cup and the plunger is then pushed forward by the spring so as to deliver the grease to the 15 bearing.

The construction above described provides a labor and trouble saving cup, the cap of which may be instantly removed and replaced and when the cap is in place it prevents the grease from escaping from the cup 20 so as to catch dirt and soil the clothing. Only one adjustment is necessary to remove the cap and plunger and to return the same to their useful positions. The plunger automatically forces the grease from the cup 25 in accordance with the feed governed by the position of the regulating screw and the movement of the grease is constant and even. A glance at the cup shows whether or not it is empty and enables a quick estimate 30 to be made as to how much grease remains in the cup. The cup will last as long as an engine, there being no threads to strip or wear out. It also effects a saving of grease, 35 an elimination of dirt, a better and even lubrication of the bearing with which it is associated and is of general convenience and utility.

What we claim is:—

- 40 1. The combination of a cup, a detachable cap therefor, one of said members being formed with oppositely located bayonet grooves having extension notches, lugs on the other member movable into and out of said grooves and notches by a combined axial and sliding movement, an expressing plunger in said cup, a plunger stem slidible through said cap, a spring arranged to

press said plunger toward the discharge end of the cup, and a bowed spring interposed between said cup and cap and pierced by said plunger stem serving to retain the cap on the cup. 50

2. The combination of a cup formed near the receiving end thereof with oppositely located bayonet grooves, a detachable cap fitting around the upper portion of said cup, lugs on the inside of said cup and movable into and out of said grooves by a combined axial and sliding movement, an expressing plunger in said cup, a plunger stem slidible through said cap, a spring arranged to press said plunger toward the discharge end of the cup, and a bowed spring interposed between said cup and cap 55 serving to retain the cap on the cup, said bowed spring forming a seat for the plunger spring. 60

3. The combination of a cup formed near the receiving end thereof with oppositely located bayonet grooves having extension notches along the upper sides thereof, a detachable cap fitting around the upper portion of said cup, lugs on the inside of said cap and movable into and out of said grooves by a combined axial and sliding movement also adapted to seat in said notches, an expressing plunger in said cup, a spring arranged to press said plunger toward the discharge end of the cup, and a bowed spring interposed between said cup and cap 70 serving to retain the cap on the cup, said bowed spring forming a seat for the plunger spring. 75

In testimony whereof we affix our signatures in presence of two witnesses. 80
